ELECTRIC SWITCH

John G. Jackson, Detroit, Mich., assignor to
 Square D Company, Detroit, Mich., a corpora-
 tion of Michigan

Application July 2, 1937, Serial No. 151,710

10 Claims. (CL 200—67)

This invention relates to electric switches and has for its object the provision of a front operating electric switch utilizing a relatively small amount of space and providing a maximum of front accessibility for the switching and manipulable parts.

Another object of the invention is an electric switch having the switching parts recessed in the front face of the base and swinging forwardly thereof to limit the operating space needed in front of the base and with operating means at the back of the base to provide accessibility to the switching parts.

Another object of the invention is an electric switch mounted within an enclosure on a hinged support providing for swinging movement of the switch to the exterior of the enclosure, with quick make and break operating means mounted on and movable with the support and with economies of space and a maximum of accessibility to the switching parts.

Another object of the invention is the provision of an improved quick make and quick break operating means for a manually operated electric switch.

Another object of the invention is the provision of an improved mounting means for an electric switch.

Other objects and features of the invention will be readily apparent to those skilled in the art from the following specification and the appended drawings illustrating certain preferred embodiments of the invention in which:

Figure 1 is a front elevational view of an electric switch according to the present invention with the cover opened.

Figure 2 is a horizontal sectional view on the line II—II of Figure 1.

Figure 3 is a partial vertical sectional view on the line III—III of Figure 1.

Figure 4 is a partial vertical sectional view on the line IV—IV of Figure 1.

Figure 5 is a partial vertical sectional view on the line V—V of Figure 1.

Figure 6 is a detailed sectional view on the line VI—VI of Figure 1.

Figure 7 is a sectional view similar to Figure 3 but directed to a construction providing for quick break operation only.

Figure 8 is a detailed sectional view on the line VIII—VIII of Figure 7.

The electric switch according to the present invention comprises an enclosing box 1 having a front cover 2 hingedly mounted thereon. Hingedly mounted to the same side wall of the box to

which the cover 2 is hinged is a generally U-shaped mounting pan 3. The opposite side wall of the box is provided with slots in which are received studs 4 threaded into the pan and tightenable against the side wall of the box to securely hold the pan within the box. Upon forwardly extending flanges 5 at the top and bottom of the pan 3 is disposed an insulating base 6 supporting the parts of the switch proper. At intermediate parts of the base slots 7 are provided extending through the base. Within the bottom portion of these slots are mounted the hinge jaws 8 having integral supporting straps 9 extending over the front of the base and secured rigidly thereto by studs 11 extending from the back of the base. Within the hinge jaws 8 are pivotally mounted knife-blade switching members 12 to which are rigidly secured generally arcuate shaped insulating blade hooks 13 extending through the slots 7 and into the space between the back of the base and the pan 3. Above the slots 7 and in line therewith the base is provided with recesses 14 communicating with the front of the base in which are disposed the contact jaws 15 having integral supporting straps 16 extending over the front of the base and there connected by means of studs 17. The aligned recesses 14 and slots 7 are connected by further cut-out portions in the base providing clearance for the knife blade 12 in its interior position.

Arc suppressor means are provided for each cooperating plate and jaw and these comprise spaced insulating plates 18 upon the exterior of which are rigidly secured magnetic brackets 19 extending along the sides of the plates 18 and joined together beneath the plates and above the contact jaws. The suppressors are mounted by a stud 21 threaded into the base or bight of the bracket 19. A metallic deflecting portion 22 bridges the plates adjacent to the front edges thereof and serves to deflect the arc from the front cover. The arc suppressor as shown and as here described is in its most complete form for the highest voltage and current rating of the switch. For the lower voltage values the insulating plates 18 and deflecting portion 22 are omitted and the arc suppressor is formed entirely by the magnetic bracket 19. For the higher voltages the plates 18 are mounted on the brackets 19 and for the highest ratings the deflecting portions 22 are used. This arrangement provides for common parts used on different switch ratings readily adaptable by the addition of other parts to the higher rated switches. Connected to the straps 9 are upper fuse clips 23 and spaced

therefrom are the cooperating lower fuse clips 24, all mounted on the front face of the base. Barrier portions 25 integral with the base are provided and auxiliary barrier walls of insulation 26 are also provided on the front face of the base.

At the back of the base 6 the arcuate hooks 13 are provided adjacent their unattached ends with notches 27 against one of the ends of which is disposed a generally U-shaped operating bail 29. This bail is mounted for rotation in the opposite vertical side walls of the pan 3 and at the side opposite the hinges thereof extends for a considerable distance beyond the enclosing box for connection to the exterior operating handle. Stops 31 are rigidly connected to the opposite side walls of the pan to limit the extremes of movement of the bail. The bottom of the pan adjacent its hinged side is provided with an elongated cup extension 32 to which is hingedly mounted a spring guide 33 having a slot 34 adjacent its free end receiving the horizontal portion of the bail 29. A compression spring 35 is mounted about the arm 33 and exerts its force between the bail 29 at the front and flanges 36 on the arm 33 at the back. To the portion of the bar 29 exterior to the box there is rigidly secured a disc 37 having a pin 38 rigidly mounted eccentrically thereof. The disc 37 is mounted by means of a hub 39 rigid therewith and rigidly secured adjacent to the end of the bail 29. About the hub 39 is disposed a spiral spring 41 having its end portions 42 and 43 disposed on opposite sides of the pin 38. The exterior operating handle 44 includes a cup shaped hub 45 having at its inner periphery a projection 46 also disposed between the ends 42 and 43 of the spring 41, and with projections 47 and 48 which are spaced about and disposed at opposite sides of a second pin 49 rigid with the disc 37. The handle 44 is movable relative to the disc 37 and the bail 29 between the stops formed by the projections 47 and 48 as they engage with the pin 49. The handle 44 is mounted on the bail 29 in any desired manner, as shown by a pin and washer arrangement 51. The side wall of the box opposite the hinges is provided with a slot 52 receiving the bail 29 in the interior position of the switch.

The mounting pan 3 is mounted with its back portion spaced from the back wall of the base in order to provide a space for circuit wires and it is to be noted that this pan together with the cup 32 act to entirely shield the wires from contact with moving parts.

The operation of the switch will now be described. To draw in circuit wires or connect conduit, etc., it is desired to have the interior of the box as accessible as possible. Hence, for this and other similar operations the studs 4 are loosened and the entire switch swung outwardly on the pan 3 to the box exterior leaving the interior of the box entirely empty. After this operation the switch may be again swung to its interior position whereupon the bail arm 29 passes into the slot 52 and the studs 4 are received within their slots and thereafter tightening of the studs 4 will rigidly secure the switch within the enclosing box in operating position. To operate the switching parts the exterior handle 44 is pulled downwardly and upwardly. When in its upper position as viewed in Figure 1, the parts are in the closed circuit position with the contact ends of blades 12 engaged within the jaws 15. When the handle is pulled downwardly from this position tension is first built up in the spring 41 by movement of the spring end 43 caused by engagement there-

with of the extension 46 on the handle hub while the spring end 42 remains stationary due to its engagement with pin 38 since the bail 29 and disc 37 have not yet moved. This spring pressure builds up until the stop 48 engages the pin 49 and thereafter the disc 37 and ball 29 are positively moved by movement of the operating handle. As the bail 29 rotates it depresses spring 35 and at the same time moves it toward dead center position. Just before the dead center position of the spring 35 the force stored in spring 41 becomes greater than the force necessary to throw spring 35 over center and when this occurs the movement of bail 29 through the dead center position of spring 35 is effected quickly by the expenditure of the energy stored in spring 41 and this movement is effected independently of further movement of the operating handle 44. As this movement occurs the bail 29 engages the base of the U-shaped bracket 28 and moves the arcuate members 13 which in turn move the blades 12 to which they are connected into the open circuit position as shown in Figure 4. The point at which the energy in spring 41 throws the spring 35 over center occurs before the blade 12 leaves the jaw 15 so that a true quick break is effected. As the spring 35 has passed over center the energy of this spring serves to move the bail 29 to its full open circuit position. In moving the parts to closed circuit position the operation is in reverse as here the spring end 42 is compressed until stop 47 engages pin 29 when the movement of the bail becomes positive with respect to the operating handle. Again the energy in spring 41 throws the spring 35 back over center and this occurs before the blades 12 have engaged their jaws 15. In this movement the bail 29 is pressing against the end of the slot 27 opposite to that in which the bracket 28 is disposed. While the spring 35 has only one dead center position the spring 41 serves to throw it through this position independently of the outside handle so that there is formed an operating characteristic resulting in two effective dead center positions at either side of the true dead center position of the spring 35. This enables the setting of one dead center position before the contacts disengage in moving to open circuit position and the other before the contacts engage in moving to closed circuit position, thus providing for true quick make and true quick break operation.

Due to the positioning of the hinge jaw 8 within the slot 7 and the contact jaw 15 within the recess 14 it is noted that while the blade 12 is of considerable length in its open position it extends forwardly a lesser distance than in conventional type switches wherein the jaws are mounted forwardly of the base. This provides for a compact structure and the disposition of the operating bail and other parts at the back of the base leaves the front entirely clear for access while providing a relatively short depth to the working parts over what would be expected of the conventional structure. The front of the base is entirely free for manipulation and connection without the inconvenience of a front operating bail and the switching blades operate forwardly so as to be readily accessible for inspection and manipulation and at the same time a compact switch structure results.

A simplified arrangement providing for quick break switch operation only but utilizing the same switching parts previously described is illustrated in Figures 7 and 8. Here the bail 29, handle 44, over center spring 35 and associated

parts, spring 41 and all the parts associated with these have been replaced by a single continuous bail 53 which is of one piece and supported in the opposite sides of the pan 3 and extending to the exterior of the box where it is bent over to form the operating portion 54. Within the bracket 28 is disposed a leaf spring 55 which in its released position biases the bail 53 against the side of slot 27 opposite the bracket 28. In the operation of this switch the contacts engage with a positive action but on the break as the handle 54 is moved downwardly the bail 53 moves into the bracket 28 compressing the spring 55. When the spring 55 is compressed against the back of the bracket the movement becomes positive and remains positive until the blade 12 is leaving the jaw 15 whereupon the force stored in spring 55 becomes greater than that necessary to move the blade and the blade is snapped open by the release of the spring energy independent of the movement of the handle 54. This structure provides a simple and inexpensive quick break mechanism utilizing the identical base and switching parts of the more expensive switch construction previously described and substitutes a simple continuous bail and leaf spring for the over center and spiral springs and relatively movable handle and bail previously described. This results in the production of a full quick make and quick break operating switch and a simple quick break only operating switch with the majority of parts common so that greater standardization and increased production at lowered cost result.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What is claimed is:

1. In an electric switch, an enclosing box having an openable cover, a hingedly mounted supporting pan mounted on said box in spaced relation to the back wall thereof, an operating bail pivoted in said pan and movable therewith, a cup-shaped extension on the back surface of said pan, a spring guide pivotally mounted in said extension and engageable with said bail, a compression spring about said guide and adapted to be moved through a dead center position by movement of said bail, a manually engageable handle portion at the exterior of said box for effecting movement of said bail, an insulating base mounted on said pan in front of said bail, switching elements mounted on the front face of said base, and operating means attachable to said elements and extending through said base into engagement with said bail for effecting movement of the switching parts in response to movement of the bail to perform the switching operation.

2. An electric switch comprising an enclosing box having an openable cover, a supporting pan hingedly mounted on said box in spaced relation to the back wall thereof, an insulating base mounted on said pan, switching elements on said base, an operation crank pivotally mounted on said pan and having a lost motion connection with said elements, an over-center spring mounted on said pan and connected to said crank, an operating handle at the exterior of the box and having a lost motion connection with said crank, and a torsion spring having its opposite ends en-

gageable by portions respectively rigid with said handle and crank whereby a spring bias is placed on said crank by movement of the handle in either direction, said spring bias being sufficiently strong to quickly move the crank through the dead center position of said over-center spring.

3. An electric switch comprising an enclosing box having an openable cover, a supporting pan hingedly mounted on said box in spaced relation to the back wall thereof, an insulating base mounted on said pan in spaced relation thereto, switching elements mounted on the front face of said base and having operating means connected thereto and extending to the back of the base, an operating crank disposed between the back face of said base and said pan and having a lost motion connection with said operating means, over-center spring means connected to said crank, an exterior operating handle having a lost motion connection with said crank, and a torsion spring connection between said handle and crank adapted to apply a spring bias on said crank upon movement of the operating handle sufficiently strong to quickly throw said over-center spring through its dead center position.

4. An electric switch comprising a base, a plurality of recesses in the front face of said base, hinge and contact jaws disposed in paired spaced relation in each of said recesses, a contact blade hingedly mounted on each of said hinge jaws and adapted to cooperate with the paired contact jaws to perform the switching operation, openings to the back of the base communicating with each of said recesses, insulating means connected to said blades and extending through said openings to the back of the base, a bracket interconnecting said insulating means at the back of the base, an operating bail disposed at the back of the base and having a lost motion connection with said bracket, over-center spring means connected to said bail for moving the same to its opposite extreme positions, and a manually operable means having a lost motion connection with said bail to effect movement thereof to perform the switching operation.

5. An electric switch comprising a base, a plurality of recesses in the front face of said base, hinge and contact jaws disposed in paired spaced relation in each of said recesses, a contact blade hingedly mounted on each of said hinge jaws and adapted to cooperate with the paired contact jaws to perform the switching operation, openings to the back of the base communicating with each of said recesses, insulating means connected to said blades and extending through said openings to the back of the base, a bracket interconnecting said insulating means at the back of the base, an operating bail disposed at the back of the base and having a lost motion connection with said bracket, over-center spring means connected to said bail for moving the same to its opposite extreme positions, an operating handle having a lost motion connection with said bail, and a torsion spring interconnecting said handle and bail and operating to quickly move the bail through the dead center position of said over-center spring.

6. An electric switch comprising a base, an opening through said base, a conducting support disposed in said opening, a recess in the front face of said base aligned with said opening, a contact jaw disposed within said recess, a contact blade hingedly mounted on said support and adapted to be received in said contact jaw to complete the circuit through the switch, said

blade in its closed circuit position within the jaw having at least the major portion thereof located below the front face of the main body of the base, a blade hook attached to said contact blade and extending through said opening to the back of said base, and operating means at the back of the base engageable with said blade hook to rotate the blade forwardly of the front face of the base to effect the switching operation.

7. An electric switch comprising a base, a recess in the front face of said base, a conducting support and contact jaw disposed in said recess in spaced relation, a contact blade hingedly mounted on said support and adapted to cooperate with said contact jaw to perform the switching operation, said blade in its closed circuit position within the jaw having at least the major portion thereof located within the recess below the front face of the main body of the base, an opening from the back of the base communicating with said recess, means attached to said contact blade for moving the same and extending through said opening to the back of the base, and operating means at the back of the base engageable with said first mentioned means to effect rotation of the blade forwardly of the front face of the base to effect the switching operation.

8. An electric switch comprising a supporting surface, an insulating base mounted in spaced relation to said surface, a recess in the front face of said base, hinge and contact jaws disposed in said recess in spaced relation, a contact blade hingedly mounted to said hinge jaw and adapted to rotate forwardly of the front face of the base into and out of said recess in co-operating relation with said contact jaw to perform the switching operation, said blade when in engagement with the jaw having at least the major portion thereof located below the front face of the main body of the base, at least a portion of said recess extending through to the back face of the base, means attached to said contact blade for moving the same and extending through said portion, and an operating bail disposed between said base and said supporting surface and engaging with said means to effect

rotation of the blade into and out of engagement with the contact jaw.

9. An electric switch comprising a supporting surface, an insulating base mounted in spaced relation to said surface, a recess in the front face of said base, hinge and contact jaw disposed in said recess in spaced relation to said surface, a contact blade hingedly mounted in said hinge jaw and adapted to rotate forwardly of the front face of the base into and out of said recess in co-operating relation with said contact jaw to perform the switching operation, said contact blade when received within the jaw having at least a major portion thereof located within the recess below the front face of the main body of the base, at least a portion of said recess extending through the back face of the base, means attached to said blade for moving the same and extending through said portion, an operating ball disposed between said base and said supporting surface and engaging with said means to effect rotation of the contact blade into and out of engagement with the contact jaw, and a readily releasable connection between said bail and said means providing for ready removal of the base and the parts supported thereon without disturbing the ball.

10. An electric switch comprising a base, an opening through said base, a conducting support disposed in said opening, a recess in the front face of said base aligned with said opening, a contact jaw disposed in said recess, a contact blade hingedly mounted on said support and adapted to be received in said contact jaw to close the circuit through the switch, said blade when engaged in said jaw having at least the major portion thereof located below the front face of the main body of the base, a blade hook attached to said contact blade and extending through the opening of said face to the back of the base, operating means disposed at the back of the base and the lost motion connection between said operating means and blade hook, said connection including a spring compressible by movement of the operating means to effect movement of the blade to disengaged position, said spring expending its stored energy to secure a quick break operation of the contact blade.

JOHN G. JACKSON.
